ATOMIZER

Irving Florman, New York, N. Y.

Application May 16, 1935, Serial No. 21,863

2 Claims. (Cl. 299—97)

My invention relates to atomizers for perfumes and similar fluids.

The primary object of my invention is to provide an atomizer which is simple and easy to operate, and which can be made inexpensively and from a few parts, all of which may be produced by the screw machine process and without bending or soldering.

A further object of the invention is to provide an atomizer in which the fluid supply chamber is shut off when the device is not in use, and in which operation of the device automatically establishes communication with such chamber.

A further object of the invention is to provide a mechanism of this type in which a novel and extremely efficient arrangement for breaking up the stream of perfume into a spray or mist, or in other words for really atomizing the perfume, is provided.

20 Further objects and advantages of the invention will appear more fully from the following description, particularly when taken in conjunction with the accompanying drawing which forms a part thereof.

25 In the drawing:

Fig. 1 is a side elevation of an atomizer embodying my invention, with the top removed.

Fig. 2 is a vertical cross section.

30 Figs. 3 and 4 are cross sections on the lines 3—3 and 4—4 respectively of Fig. 2.

Fig. 5 is an enlarged perspective view of the atomizing member.

As shown in Fig. 2, the atomizing mechanism comprises a body portion or casing 2 having a 35 chamber 4 therein for receiving the perfume or other fluid to be atomized. This casing is provided in its top with an opening 6 in which may be threaded a piston member 8 having a downwardly extending portion 10 which fills 40 and closes the opening 6. A washer 12 of rubber or other suitable material may be placed between the bottom of the piston member 8 and the top wall of casing 2 in order to seal the joint therebetween.

45 Below the extension 10 piston member 8 has a further extension 14 of smaller diameter, also externally threaded, and smaller than aperture 6. On this member 14 is threadedly secured a tube 16, the lower portion of which is first tapered inwardly as at 18 and then has a smaller 50 downwardly extending portion 20 which extends almost to the bottom of chamber 4. Within the tapering portion 18 is a ball 22 acting as a valve for which the tapering portion 18 forms the 55 seat, and above this ball is a perforated retain-

ing disc 24 suitably arranged to prevent the escape of the ball and to act as a support for the spring to be described below.

The upper central portion 26 of the member 8 acts as a piston, and outside of this portion is 5 an annular groove 28 and an annular outer wall or guide wall 30, integral with piston portion 26. Vertically slidable in the annular groove 28 is a cylinder member 32, which fits tightly within the groove and forms with piston member 8 a 10 space 34 cooperating as a cylinder with the piston portion 26. The top of the cylinder space 34 is closed by a wall 36, which is preferably rounded on top to provide a suitable smooth surface for operation by the finger of the user. 15

Piston member 8 is provided with a vertical central passage 38 through which extends a rod 40 slightly smaller in diameter than passage 38, and threaded at its upper end in the top wall 36 of cylinder 32. The lower end of rod 40 extends through tube or pipe 16, and is provided near the top of that tube with an annular flange 42 of greater diameter than passage 38. A coil spring 43 is arranged in tube 16, resting at one end on plate 24 and at the other end engaging 20 flange 42. The diameter of flange 42 is somewhat less than the inside diameter of tube 16, or in any event is so arranged that fluid may 25 pass upwardly through the tube, and also through passage 38, without interference from flange 42 except when the same is in its raised 30 position against the bottom of member 8.

From the cylinder 34, fluid may escape through passage 44 into recess 46. Recess 46 extends out to one side of top wall 36, and within 35 the recess is arranged a nozzle member 48 having a nozzle opening 50 of reduced size to permit the escape of atomized fluid. The member 48 has a tube-like portion 52 extending within the bore 46, and within portion 52 and the 40 bore is arranged a helix 54 (Fig. 5) which substantially fills the bore, and which consists of a plug or rod, of substantially the same diameter as extension 52, and provided with a pair of helical grooves in its surface. By this construction, the fluid passing through the bore is forced 45 to follow the configuration of the helix. This imparts a swirling motion to the fluid and causes it to be atomized or broken up into a fine mist as it leaves the nozzle aperture 50. 50

The atomizer may be closed and covered when not in use by a cap or cover 56, which may be threadedly secured on the base or reservoir 2.

The operation of the device is very simple. The wall 32 fits very closely within the groove 28, 55

so that the connection is substantially air-tight, or at least sufficiently so for the operation of the device. If the cylinder member 32 is depressed with the finger, ball 22 will be in its lowered position and the air in the cylinder space 34 will be forced out through nozzle 48. When the pressure on the top 36 is released, the cylinder member 32 will rise suddenly and will create a reduction in pressure in the space 34 which cannot be immediately relieved through opening 50. This will cause some of the perfume to be raised up through tube 20 and past one-way ball valve 22 into the section 16. As this operation is repeated, the section 16 will gradually be filled and then perfume will be finally brought up into the chamber 34. Of course in continued operation thereafter each use of the atomizer will draw in more of the fluid and will thereby replace in the chamber 34 perfume which may have been removed therefrom.

As soon as the perfume is present in chamber 34, depression of member 36 will cause the perfume to be ejected through helix 54 and nozzle 50 in a fine spray. This perfume then escapes from the device in atomized condition as is desired.

Each time the member 36 rises under the action of spring 43, the flange 42 will be pressed against the bottom of the piston member 8 and thereby will close the lower end of passage 38. This will seal within the container all perfume below this level and will prevent losses by evaporation of any large quantities even though the device may stand for some time without use.

35 In order to fill the atomizer, the piston member 8 may be unscrewed as a whole, and the fluid poured through opening 6 into the reservoir. Member 3 may then be replaced.

While I have described herein one embodiment 40 of my invention, I wish it to be understood that I do not intend to limit myself thereby except within the scope of the appended claims.

I claim:

1. In an atomizer, a body portion having a 45 fluid chamber therein, and an opening in said chamber, a piston member secured in said opening, said member having a passage therethrough, a tube secured on the lower end of said member, in communication with said passage, said tube 50 being arranged within said fluid chamber, and having a relatively large upper portion of less diameter than said opening, a section of decreasing diameter, and a lower portion of reduced size terminating at a point adjacent the bottom 55 of the chamber, said decreasing section forming a valve seat, a ball valve within said last section forming therewith a one-way valve, a perforated plate within said tube above said valve, said piston member at its upper end including a piston 60 ton portion, a cylinder member comprising a

closure wall and an annular wall extending therefrom, said last wall forming a cylinder space within which said piston acts, a rod secured to said cylinder member and extending downwardly through the passage in said piston member 5 into the upper end of said tube, said rod being of less diameter than said passage, a flange on said rod within said tube of greater diameter than said passage, and a coil spring in said tube resting at one end on said plate and at the other end 10 engaging said flange, whereby when said cylinder member is raised by the pressure of the spring said flange closes the lower end of said passage, a nozzle, and means connecting said nozzle to the interior of the cylinder member. 15

2. In an atomizer, a body portion having a fluid chamber therein, and an opening in the top of said chamber, a piston member threadedly secured in said opening, said member having a passage therethrough, a tube threadedly secured on the lower end of said member, in communication with said passage, said tube being arranged within said fluid chamber, and having a relatively large upper portion of less diameter than said opening, a section of decreasing diameter, and a lower portion of reduced size terminating at a point adjacent the bottom of the chamber, said decreasing section forming a valve seat, a ball valve within said last section forming therewith a one-way valve, a perforated plate 30 within said tube above said valve, said piston member at its upper end including a piston portion and an annular guiding wall around the piston portion and spaced therefrom, forming an annular groove therebetween, a cylinder member comprising a horizontal top wall and a downwardly extending annular wall fitting in said groove, said last wall forming a cylinder space within which said piston acts, a rod threaded in said horizontal top wall and extending downwardly through the passage in said piston member into the upper end of said tube, said rod being of less diameter than said passage, a flange on said rod within said tube of greater diameter than said passage, and a coil spring in 45 said tube resting at one end on said plate and at the other end engaging said flange, whereby when said cylinder member is raised by the pressure of the spring said flange closes the lower end of said passage, a recess in one side of said horizontal wall, means connecting said recess to the interior of the cylinder member, a nozzle member having a tube-like portion fitting within said recess, and a nozzle aperture, and an atomizing member comprising a plug fitting within and substantially filling said tube-like portion and having in its periphery at least one helical groove. 50 55
